UNITED STATES PATENT OFFICE.

ISAAC H. VENN, OF YONKERS, NEW YORK, ASSIGNOR, BY MESNE ASSIGNMENTS, TO THE NATIONAL COMPANY, OF ILLINOIS.

HYDRAULIC ELEVATOR.

SPECIFICATION forming part of Letters Patent No. 476,581, dated June 7, 1892.

Application filed July 25, 1889. Serial No. 318,652. (No model.) Patented in England November 5, 1889, No. 17,604; in Germany November 5, 1889, No. 55,799; in France November 5, 1889, No. 201,725, and in Italy December 31, 1889, No. 499.

To all whom it may concern:

Be it known that I, ISAAC H. VENN, a citizen of the United States, residing at Yonkers, county of Westchester, and State of New York, have invented certain new and useful Improvements in Hydraulic Elevators, fully described and represented in the following specification and the accompanying drawings, forming a part of the same, the said improvements being embraced in British Letters Patent No. 17,604, dated November 5, 1889; in German Letters Patent No. 55,799, dated November 5, 1889, and in French Letters Patent No. 201,725, dated November 5, 1889, and in Italian Letters Patent No. 499, dated December 31, 1889.

This invention relates to improvements in hydraulic elevators, its object being to economize in the consumption of water in those elevators of this class which employ what is known as the "circulating system"—that is to say, those elevators in which during the descent of the car the water circulates from one side of the motor-piston to the other.

In the elevators of this class the water is admitted to one end of the motor-cylinder, herein for convenience called the "induction end," to act upon the piston and raise the car, and when the car is to descend the water is allowed to circulate to the other end of the cylinder, herein for convenience called the "ejection end," thereby permitting the car to descend by its own weight. By this system the water always acts at full pressure upon the motor-piston during the ascent of the car. If the car is carrying its maximum or substantially its maximum load, the full pressure of the water upon the piston is required and no waste of power results. If, however, the car is empty or carries but a light load, the full pressure of the water upon the piston is not required to raise the car, and as a consequence the piston is driven against the water in the ejection end of the cylinder and exerts a pressure tending to force the water out of the cylinder, which force is entirely wasted, as it performs no useful function. From this it will be seen that the same amount of water is consumed and the same power expended at

each ascent of the car regardless of whether the car is empty or heavily loaded.

It is one of the objects of the present invention to provide means by which when the car is ascending with no load or less than the maximum load the surplus power developed by the water acting upon the induction side of the motor-piston will be utilized to cause the circulation of a part of the water contained in the ejection end of the cylinder from that end of the cylinder to the induction end, thereby causing the amount of water consumed at each ascent of the car to conform approximately to the load, and thus economize in the consumption of water. When the car is descending, the weight of the car and its load move the motor-piston along the cylinder and cause the water to circulate from the induction to the ejection end of the cylinder. When the load is light, the pressure tending to force the water out of the induction end of the cylinder is comparatively small, but when the load upon the descending car is heavy the piston is moved along the cylinder with such power as to expel the water from the cylinder with considerable force.

Another object of the present invention is to provide means by which the surplus power developed by the descending car and its load will be stored up and subsequently utilized in raising the car and its load.

A full understanding of the invention can be best given by an illustration and a detailed description of an organized elevator mechanism embodying the same. Such description will therefore be given, reference being had to the accompanying drawings, in which—

Figure 1 is a sectional elevation of the motor-cylinder, valve, and circulating-pipe of a hydraulic elevator of the class referred to, showing the present invention applied thereto. Fig. 2 is a vertical section taken on the line 2 of Fig. 1. Fig. 3 is a horizontal section taken on the line 3 of the same figure. Fig. 4 is an elevation of an elevator mechanism embodying the invention in a slightly-modified form. Fig. 5 is an enlarged vertical sectional view of a portion of the same. Figs. 6

and 7 illustrate other modifications, which will be hereinafter explained.

Referring to said drawings, it is to be understood that A represents the motor-cylinder and B the circulating-pipe of a hydraulic elevator of the class referred to. The cylinder is provided with the usual piston, the rods C of which are connected to the hoisting cable or cables of the elevator in the usual manner. The cylinder A is herein shown as arranged vertically; but this is not essential, as it may be arranged horizontally, if preferred.

The circulating-pipe B is provided with a valve D, which controls the induction of the water to the upper end of the cylinder, its circulation to the lower end, and its final discharge in the usual manner. The valve D is in the case illustrated of the construction shown and described in the joint application of myself and R. C. Smith, filed February 2, 1889, Serial No. 298,479, although it may be of any other suitable form. The valve D may be operated in any of the ways common in this class of elevators.

The water for operating the elevator is supplied from a supply-pipe H, which in the case shown communicates with the chest of the valve D, and thence through the circulating-pipe B with the induction end of the cylinder A, so that a part of the circulating-pipe becomes, also, a part of the supply-pipe. This, however, is not essential. If a valve of a different form is used, the supply-pipe may communicate directly with the cylinder, as is common.

The pipe B will for convenience be herein referred to as the "supply" and "circulating" pipe; but it is to be understood that an organization in which separate supply and circulating pipes are employed is in a broad sense the equivalent of that shown. The supply and circulating pipe is provided with two reversely-arranged nozzles E F, through the former of which the water must pass in entering the induction end of the cylinder and through the latter of which it must pass in circulating to the eduction end of the cylinder. The portion b of the pipe B between the nozzles E F is reversely tapered, so as to cooperate with the nozzles to form injectors of the ordinary form. At the points occupied by the nozzles E F the pipe B is enlarged, so as to form chambers a c around the respective nozzles. In the organization shown in Fig. 1 the chamber a communicates through one or more openings d with the circulating-pipe B between the valve D and the eduction end of the cylinder. The chamber c communicates by a pipe f with a tank G, into which the waste water is discharged through a pipe I, or the pipe f may communicate with any other convenient source of water-supply. The tank G is of course provided with a suitable overflow-pipe, by which the surplus waste water can escape. It is of course to be understood that if separate supply and circulating pipes are employed the nozzle E will be in the sup-

ply-pipe and the nozzle F in the circulating-pipe.

In the organization of the invention illustrated in Figs. 1 and 2 the nozzle E is located slightly below the portion of the pipe B which connects the eduction end of the cylinder and the chest of the valve D, and the tank G is located slightly above the level of the nozzle F. By this means water enters the chambers a c under a slight head, which aids the inductive action of the injectors, and although in many cases this is the preferable organization, it is not essential.

Figs. 4 and 5 show an organization in which the nozzle E is located above the portion of the pipe B which connects the eduction end of the cylinder A and the casing of the valve D, the chamber a being connected to the pipe B by a pipe y, and in which the tank G is below the level of the nozzle F. In this case the water will not flow to the chambers a c under any head, but will have to be drawn into the chambers by the inductive action of the injectors.

The operation of the organization as thus far described is as follows: When it is desired to cause the car to ascend, the valve D is moved into position to open communication from the eduction end of the cylinder to the waste-pipe I, and also (if the valve controls the supply-pipe, as is shown in the present case) open communication through the supply-pipe to allow the water to enter the induction end of the cylinder. Water will then pass from the pipe H through the valve-chest and enter the pipe B, and passing upward through the nozzle E enter the induction end of the cylinder and drive the piston downward, so as to raise the car, the water contained in the eduction end of the cylinder beneath the piston being at the same time allowed to flow outward to the main discharge-pipe I.

If the car is carrying the maximum or substantially the maximum load, the full pressure of the water upon the piston will be required to raise the car, and as a consequence no pressure will be developed upon the water in the eduction end of the cylinder, which will simply flow out as the piston descends. If, on the other hand, the load is light or comparatively light, the full pressure of the water upon the piston will not be required to raise the car, and as a consequence the piston will tend to develop a greater speed, thereby exerting a pressure upon the water beneath it, tending to force the same out of the cylinder. The increased speed of the piston will cause the water to flow through the pipe B more rapidly, so that as the incoming water is forced through the contracted opening of the nozzle E it will acquire a considerable velocity, so as to create an inductive action the same as in the ordinary injector, which will cause more or less of the water from the chamber a to enter the pipe B around the nozzle and be carried into the

induction end of the cylinder. By this means a portion of the water in the eduction end of the cylinder is circulated back and restored to the induction end of the cylinder, thereby 5 economizing in the consumption of water and proportionately reducing the expense of operating the elevator.

When it is desired to cause the car to descend, the valve D is shifted so as to open 10 communication through the pipe B between the induction and eduction ends of the cylinder. Both ends of the cylinder will then be in communication with the supply-pipe H, and as a consequence the pressure upon the 15 opposite sides of the piston will be equal and the car will descend by its own weight, the water in the induction end of the cylinder passing through the circulating-pipe and entering the eduction end of the cylinder as the 20 piston ascends.

When the car is descending with no load or only a light load, the piston in the cylinder will not be moved upward with sufficient force to drive the water out of the induction 25 end of the cylinder under much pressure, and it will consequently circulate gently from the induction to the eduction end of the cylinder. When, however, the descending car is heavily loaded, the power developed by the load will 30 drive the water out of the induction end of the cylinder with great force, so that it will issue from the nozzle F with great velocity, and will thus act inductively to draw in a 35 quantity of water from the tank G, which will be added to the volume available for use in raising the car. By this means the power developed by the descending load is stored up for future use.

In order to prevent the incoming water 40 from entering the chamber a and passing through the openings d to the waste-pipe when the load is so heavy or the flow of the water through the nozzle E is so slow that there is no inductive action developed by the 45 injector, and also to prevent the water from escaping during circulation, the openings d are provided with check-valves g, which permit the water to flow from the eduction end of the cylinder to the chamber a, but prevent 50 it from flowing in the opposite direction. In order to prevent the incoming water from passing through the pipe f to the tank G and also to prevent the circulating water from escaping in the same manner when the load 55 upon the car is light, the pipe f is provided with a check-valve h, arranged similarly to the valves g.

The nozzles E F may and preferably will be adjustable, so that the space through which 60 the water is drawn by the inductive action of the injectors can be varied as different conditions may require. This may be effected in a variety of ways.

One convenient form of mechanism for adjusting the nozzles is illustrated in Fig. 1 in connection with the nozzle E. For this purpose the nozzle is provided upon its side with

a rack k, which is engaged by a small pinion l, mounted upon a shaft, which extends through a stuffing-box and is provided with 70 a handle (not shown) by which it can be conveniently operated. The nozzle F may of course be provided with a similar apparatus.

Where both of the nozzles E F are, as illustrated in the present case, located in the same 75 pipe, which serves both as a supply and a circulating pipe for the motor-cylinder, it is desirable that means should be provided by which the entire volume of water when entering the induction end of the cylinder will 80 not be required to pass through the nozzle E and by which the entire volume of water when circulating will not be required to pass through the nozzle F. This is desirable because the passage of the water through 85 the contracted openings of the two nozzles throttles it more or less and subjects it to an unnecessary amount of friction. To avoid this, each of the injectors may be provided with a by-pass communicating, respectively, 90 with the chambers a c and with the pipe B below and above the respective injectors. The by-passes v are provided with reversely-arranged check-valves z, which act to compel the water when entering the induction end of 95 the cylinder to pass through the nozzle E, but permit it to pass around the nozzle F. During the circulation of the water the operation is reversed and the water is compelled to pass through the nozzle F, while a part of 100 it is permitted to pass around the nozzle E.

In some cases it is desirable to provide means for automatically regulating the flow of the water into the induction end of the cylinder to conform to the pressure of the water and the load to be raised, so that as the 105 pressure upon the water beneath the piston increases the flow of water into the induction end of the cylinder will be diminished, and vice versa. An organization by which this may be accomplished is also illustrated in Fig. 1. For this purpose the nozzle E is provided with a cone-shaped valve O, which is located within the nozzle, and is so arranged that as it is raised and lowered it contracts and enlarges the opening for the passage of the water through said nozzle, thus diminishing and increasing the supply to the induction end of the cylinder. The valve O is supported by arms p, which project from 110 a rock-shaft q, having an arm r, which is pivotally connected to the rod s of a piston or diaphragm t, which is subjected to the pressure of the water in the eduction end of the cylinder, and is so arranged that as the pressure 115 in the eduction end of the cylinder increases it will, through the connections which have just been described, move the valve O, so as to reduce the flow of water to the induction end of the cylinder, and vice versa. The rod 120 s of the piston t is also connected to a bell-crank lever m, which is fulcrumed at n, and is provided with an adjustable weight w, by 125 which the piston t is prevented from being 130

5 moved to any considerable extent until a certain predetermined pressure is obtained in the eduction end of the cylinder. A spring 10 may of course be used in place of the weight 15 *w* for this purpose. Where the main valve 20 D is of the character herein shown, the supply-pipe H will of course communicate directly with the valve-chest, as shown; but where other forms are employed the supply 25 pipe may connect with the circulating-pipe at any point between the main valve and the nozzle E.

15 In operating elevators equipped with the injector - nozzles it may sometimes happen, 20 when the load to be raised very nearly equals the hoisting capacity of the elevator or when the car is to descend without any load and is consequently almost held in equilibrium by the counterbalancing-weights, that it will be 25 desirable to allow the water or at least a part of it to enter the induction end of the cylinder or to circulate from the induction to the eduction end of the cylinder without being subjected to even the slight retardation due 30 to passing through one of the injector-nozzles E F. Figs. 6 and 7 show organizations in which this is accomplished in two different ways.

35 In the organization shown in Fig. 6 the pipe B is provided with a by-pass K, which passes around both of the injector-nozzles E F, and thus affords a channel through which the water or a part of the water can enter the induction end of the cylinder without passing 40 through the nozzle E and by which, also, the water or a part of it can circulate from the induction to the eduction end of the cylinder without passing through the nozzle F. As shown in Fig. 6, the by-pass K is controlled 45 by a valve *e*, the rod of which is forked and provided with a pin which passes through a cam-groove *x*, formed in the rod of the main valve D. The cam *x* is so shaped that so long as only a medium or ordinary range of movement is given to the valve D the valve *e* will 50 remain in its closed position and prevent any flow of water through the by-pass K. So long as the valve *e* remains closed the operation of the apparatus will be the same as already described. When, however, the load upon the car is almost equal to the capacity of the elevator, the valve D will be moved upward beyond the usual limit, so as to be opened to its 55 full extent, and the cam *x* is so shaped that when this takes place it will operate to open the valve *e* and allow the water or a part of the water to flow through the by-pass and enter the induction end of the cylinder without passing through the nozzle E. When the car 60 is to descend without any load, the main valve will be moved beyond the usual limit of its movement in the reverse direction, and the cam *x* is so shaped that this will also open the valve *e* and allow a part of the water to circulate without passing through the nozzle F.

65 In the organization shown in Fig. 7 the same results are accomplished in a slightly-differ-

ent manner. In this case one end of the by-pass K, instead of communicating directly with the supply and circulating pipe B, communicates with the chest of the valve D and is controlled by a valve *i*, which is carried upon the rod of the main valve. The valve *i* is so formed that as long as the main valve is not moved beyond the range of its usual movement the entrance to the by-pass remains closed. If, however, the main valve is moved beyond the limit of its usual movement in either direction, the opening to the by-pass K will be uncovered and a part of the water 80 will flow through the by-pass with the effect before stated.

85 It is of course to be understood that one of the injectors may be omitted if in any case it should not be desired to utilize the surplus power developed when the car is moving in one direction.

What I claim is—

1. The combination, with the cylinder, piston, and supply and circulating pipe or pipes 90 of a hydraulic elevator, of an injector through which the water passes in entering the induction end of the cylinder and which communicates with the eduction end of said cylinder through a passage additional to the circulating-passage between the induction and eduction ends of the cylinder, whereby the inductive action of the water passing through the injector acts to circulate water from the eduction to the induction end of said cylinder, 95 substantially as described.

2. The combination, with the cylinder, piston, and supply and circulating pipe or pipes 100 of a hydraulic elevator, of an injector through which the water passes in entering the induction end of the cylinder and which communicates with the eduction end of said cylinder through a passage additional to the circulating-passage between the induction and eduction ends of the cylinder, whereby the inductive 105 action of the water passing through the injector acts to circulate water from the eduction to the induction end of said cylinder, and a check-valve controlling said additional passage, substantially as described. 115

3. The combination, with the main cylinder, piston, and circulating-pipe of a hydraulic elevator, of an injector located in said circulating-pipe and communicating with an outside supply of water, whereby the inductive 120 action of the circulating water operates to draw in an additional supply of water, substantially as described.

4. The combination, with the main cylinder, piston, and circulating-pipe of a hydraulic 125 elevator, of an injector located in said circulating-pipe and communicating through a check-valve with an outside supply of water, whereby the inductive action of the circulating water operates to draw in an additional 130 supply of water, substantially as described.

5. The combination, with the cylinder, piston, and supply and circulating pipe or pipes of a hydraulic elevator, of an injector through

which the water passes in entering the induction end of the cylinder and which also communicates with the eduction end of the cylinder, and a second injector through which the 5 water passes in circulating and which communicates with an outside supply of water, whereby the inductive action of the water passing through said respective injectors operates to circulate water from the eduction to 10 the induction end of said cylinder and to draw in an additional supply of water, substantially as described.

6. The combination, with the cylinder, piston, and supply and circulating pipe or pipes 15 of a hydraulic elevator, of an injector through which the water passes in entering the induction end of the cylinder and which also communicates through a check-valve with the eduction end of the cylinder, and a second injector through which the water passes in circulating and which communicates through a 20 check-valve with an outside supply of water, whereby the inductive action of the water passing through said respective injectors operates to circulate water from the eduction to 25 the induction end of said cylinder and to draw in an additional supply of water, substantially as described.

7. The combination, with the cylinder, piston, and supply and circulating pipe of a hydraulic elevator, of reversely-arranged injectors located in said pipe and communicating, 30 respectively, with the eduction end of said cylinder and with an outside supply, whereby the inductive action of the water entering the induction end of said cylinder operates to circulate water from the eduction to the induction end of the cylinder and whereby the inductive action of the water in circulating 35 operates to draw in an additional supply of water, substantially as described.

8. The combination, with the cylinder, piston, and supply and circulating pipe of a hydraulic elevator, of reversely-arranged injectors located in said pipe and communicating, 40

respectively, with the eduction end of the cylinder and with an outside supply, whereby the inductive action of the water entering the induction end of the cylinder operates to circulate water from the eduction to the induction end of the cylinder and whereby the inductive action of the water in circulating 50 operates to draw in an additional supply of water, and by-passes having reversely-arranged check-valves affording communication around said injectors, substantially as described.

9. The combination, with the cylinder, piston, and supply and circulating pipe or pipes 55 of a hydraulic elevator, of an injector through which the water passes in entering the induction end of the cylinder and which also communicates with a supply of water under less pressure than the water entering the cylinder, and a valve O, controlling the flow of water 60 through the induction-nozzle and controlled by the pressure in the eduction end of the cylinder, substantially as described.

10. The combination, with the cylinder, piston, supply-pipe, and main valve of a hydraulic elevator, of an injector located in said pipe, a by-pass affording communication 65 around said injector, and a valve controlling said by-pass and operated in conjunction with the main valve, substantially as described. 70

11. The combination, with the cylinder, piston, circulating-pipe, and main valve of a hydraulic elevator, of an injector located in said pipe, a by-pass affording communication 75 around said injector, and a valve controlling said by-pass and operated in conjunction with the main valve, substantially as described.

In testimony whereof I have hereunto set my hand in the presence of two subscribing witnesses.

ISAAC H. VENN.
